ATTORNEY

UNITED STATES PATENT OFFICE.

RICHARD W. SHERRILL, OF LANDIS, NORTH CAROLINA.

SHADE-ROLLER.

1,243,561.

Specification of Letters Patent. Patented Oct. 16, 1917.

Application filed June 28, 1916. Serial No. 106,416.

To all whom it may concern:

Be it known that I, RICHARD W. SHERRILL, a citizen of the United States, residing at Landis, in the county of Rowan and State 5 of North Carolina, have invented certain new and useful Improvements in Shade-Rollers, of which the following is a specification.

This invention relates to adjustable shade 10 rollers, and more particularly to means for securing a shade in vertical adjustment within a window casing.

One of the main objects of the invention is to provide a shade roller in combination 15 with means of simple construction and operation for securing the same in any desired vertical adjustment.

A further object is to provide a device of the character stated which can be easily 20 and quickly applied to a window casing of ordinary construction.

Further objects will appear from the detailed description.

In the drawings:

25 Figure 1 is a front view of the invention as applied, partly in section.

Fig. 2 is a fragmentary detailed sectional view, and

30 Fig. 3 is a fragmentary transverse sectional view.

At each side of the window casing 1 is secured an elongated rectangular casing 2. This casing is provided with a relatively broad and deep U-slot 3 extending the full 35 length thereof. A smaller slot 4 projects inwardly from the central line of slot 2. The inner flange 2^a of the casing is provided with a series of teeth 2^b. As will be noted from Fig. 1, the teeth at the sides of 40 the window are directed in opposite directions, relatively, for a purpose to be later disclosed.

At the top and bottom of casing 2 there are mounted pulleys 5 and 6, respectively, 45 carried by brackets 7 secured to the ends of the casing. A flat ribbon or tape 8 is passed about these pulleys and has its ends secured to the ends of bracket arms 9 formed integral with a slidable head 10. These 50 bracket arms carry rollers 11 which are adapted to travel along the bottom of groove 3.

The head 10 is further provided with upwardly directed brackets 12 which rotatably support the shade roller 13 of usual construction in the usual manner. This roller

carries the shade 14 adapted to be rolled thereon. The head 10 is provided at its longitudinal center with a rectangular casing 15. The head is further provided with 60 a rearwardly projecting tubular member 16 at each end of the casing 15 and communicating therewith. A rod 17 is slidably mounted in each of the tubular members 16 and the ends of this rod are adapted to engage 65 the teeth 2^b at each side of the window. These rods are normally held in operative position by the action of a coil spring 18 mounted within the casing 15 and bearing against the lower ends of the thumb 70 levers 19 and 19^a secured on the rods 17 near the inner ends thereof. The fixed standard or abutment 20 is provided at the center of the casing 15 and cooperates with the levers 19 in a manner to be hereinafter 75 disclosed.

When it is desired to adjust the shade, it is only necessary to move one of the levers 19 inward, and at the same time, move the head 9 in the desired direction. For instance, if it is desired to raise the shade to a higher position than that shown in Fig. 1, the operator would grasp the standard 20 and force the lever 19^a inward, thus withdrawing the outer end of the rod 17 secured 80 thereto from the teeth 2^b at the left-hand side of the window. When this has been accomplished the head 9 and the shade may be easily lifted, the rod at the right-hand side of the casing easily sliding over the 85 teeth with which it engages which are upwardly inclined for this purpose. If it is desired to lower the shade, the right-hand lever 19 would be pressed inwardly and the head 9 forced downwardly the end of the 90 left-hand rod 17 readily sliding over the teeth at the left-hand side of the window. By this means the shade may be quickly 95 and easily adjusted in either direction.

Each of the casings 2 is provided, at its 100 upper end, with a bracket 21 adapted to support the curtain rod 22. By this means, the casings serve the double purpose of providing the curtain rod support and also means for adjustably supporting the shade 105 roller.

By my device, the shade may be secured in any vertical position so as to vary the amount of light which enters the room as desired. Also, if it is desired to have any 110 particular spot in the room shaded, this may be readily accomplished by adjusting the

shade for that purpose. Again, by moving the shade to a higher or lower position, the upper or lower sash of the window may be opened so as to permit ventilation of the 5 room without the shade interfering with the inflowing air current, as will be obvious.

There may be variations made in the construction and adjustment of the details of my invention, and I intend to include all 10 such variations in this application, as fall within the appended claim in which a preferred form only of my invention is disclosed.

What I claim is:

15 The combination of two spaced parallel casings each provided with a longitudinally extending series of teeth, the teeth of

one casing being directed upward and the teeth of the other casing being directed downward, a head slidably mounted between said casings, independent oppositely directed rods slidably mounted in the head and extending transversely of the same so as to engage the teeth of said casings when extended, and means for normally holding 20 said rods in extended position, said means being resilient whereby inward movement of the rods is permitted.

25 In testimony whereof I affix my signature in presence of two witnesses.

RICHARD W. SHERRILL.

Witnesses:

J. P. LINN,
E. L. FLEMING.
